UNITED STATES PATENT OFFICE.

FREDERICK W. SCHENMEYER, OF ALBANY, NEW YORK.

SHADE AND CURTAIN FIXTURE.

Application filed May 11, 1922. Serial No. 560,133.

To all whom it may concern:

Be it known that I, FREDERICK W. SCHENMEYER, a citizen of the United States, residing at Albany, in the county of Albany and State of New York, have invented certain new and useful Improvements in Shade and Curtain Fixtures, of which the following is a specification.

This invention relates to shade and curtain fixtures of the type shown in Letters Patent, No. 1,350,623, granted to me August 24, 1920. In my said Letters Patent, I disclosed a bracket or support which was adapted to receive and hold a shade roller fixture and also support straight curtain rods provided at or near their ends with perforations or sockets. The object of my present invention is to provide means whereby a flat curtain rod may be supported edgewise upon the fixture so that the field of usefulness of the device will be increased.

In the accompanying drawings—

Figure 1 is an elevation of the upper portion of a window with a pair of my improved fixtures in position thereon;

Fig. 2 is an enlarged perspective view of the fixture, the shade roller brackets being omitted and a portion of a flat curtain bar being shown;

Fig. 3 is a transverse section;

Fig. 4 is a detail perspective view showing another embodiment of the invention.

The window sash 1 and the window frame 2 are of the usual or any preferred form and my improved fixtures are secured to the edges of the window frame, as at 3. My present fixture comprises a forwardly projecting arm 4 from which a bar 5 extends at a right angle, the said bar being provided with notches 6 to be engaged by the shade roller bracket 20, one of which has been indicated on the left side of the window in Figure 1 and as fully set forth in my aforesaid Letters Patent. The arm 4 is provided at its front end with the vertically disposed spurs or pins 7 which are adapted to be engaged in openings or sockets at the ends of straight curtain rods, it being readily noted that the fixtures are reversible so that they may be applied at random to either side of the window frame. The fixture so far described, and disclosed in my above-mentioned patent, is not well adapted to support a flat curtain bar which has attained considerable commercial success and is popular with housewives. This bar, as

indicated in Fig. 2, has its ends 8 turned at a right angle to its main portion and along the edges of the bar are re-entrant flanges 9 through which at their extremities 60 are formed openings 10. To permit curtain bars of this construction to be supported upon my fixture, I have devised the support shown at 11 consisting of a forwardly projecting vertically disposed plate having a 65 central horizontal notch 12 and having vertically disposed tapering spurs 13 at its upper and lower corners. When the flat curtain bar is to be employed, the end of the same is inserted over the upstanding 70 spur 13 so that the re-entrant flange 9 will ride over said spur and engage the sides of the same with the corresponding flange at the lower edge with the bar entering the notch 12. The spur 13 will project through 75 the opening 10 in the upper re-entrant flange and the bar may thereupon be lowered slightly so that the lower flange will rest upon the lower wall of the notch 12 with the end of the flange abutting the inner vertical wall of said notch, as clearly shown in Fig. 3. The curtain may then be draped over the bar in the usual manner without any fear of the bar dropping. It will be readily noted that the support 11 is symmetrical so that it may be used with either 80 end up and, therefore, is reversible just as the fixture of which it is a part is reversible.

In Fig. 4, I have shown the device adapted to support two bars so that a valance as 90 well as a curtain may be hung. In this form of the invention, the arm 4 is omitted and a web or base 14 is secured to the bar 5 at the end thereof. At each edge of this web or base is a vertically disposed wing 95 15 projecting forwardly at a right angle to the base, each wing having a central horizontally disposed notch 16 and a vertical spur 17 at each corner.

Having thus described the invention, 100 what is claimed as new is:

1. A reversible curtain fixture comprising a bracket adapted to be attached to the side of a window frame, an arm extending along the face of said frame, a curtain support projecting substantially at right angles from said arm, a downwardly and an upwardly directed spur projecting from and beyond the corresponding edges of said support, said support being provided with a 105 central horizontal notch between said spurs having parallel edges, said upwardly di- 110

rected spur being adapted to engage in an aperture formed in a flat curtain bar while simultaneously the upwardly facing edge of said recess engages with the bottom face of 5 said bar.

2. A reversible curtain fixture comprising a bracket adapted to be attached to the side of a window frame, an arm extending along the face of said frame, a pair of curtain supports projecting substantially at right angles from said arm, each of said supports having a pair of oppositely di-

rected tapering spurs projecting from and beyond the corresponding edges of said supports and a central notch between said spurs 15 having parallel edges, the upwardly directed spurs being each adapted to engage in an aperture formed in a flat curtain bar while simultaneously the upwardly facing edge of said recess engages with the bottom face 20 of said bar.

In testimony whereof I affix my signature.

FREDK. W. SCHENMEYER. [L. s.]
